UNITED STATES PATENT OFFICE.

HENRY H. FAWK, OF SAN FRANCISCO, CALIFORNIA.

DESIGN FOR A BRAMBLE-BIRD.

• 56,962.

Specification for Design.

Patented Jan. 25, 1921.

Application filed July 30, 1920. Serial No. 400,246. Term of patent 3½ years.

To all whom it may concern:

Be it known that I, HENRY H. FAWK, a citizen of the United States, residing at San Francisco, in the county of San Francisco and State of California, have invented a new, original, and ornamental Design for a Bramble-Bird, of which the following is a specification, reference being had to the accompanying drawing, forming part thereof.

The figure is a side view of a "bramble bird," showing my new design.

I claim:

The ornamental design for a bramble bird, as shown.

HENRY H. FAWK.
